CLAIM

The ornamental design for a tag assembly as shown and described.

DESCRIPTION

FIG. 1 is a front perspective view of a tag assembly in a first state;

FIG. 2 is a rear perspective view thereof;

FIG. 3 is a front view thereof;

FIG. 4 is a rear view thereof;

FIG. 5 is a front perspective view of the tag assembly of FIGS. 1-4 in an alternative state during a process of separation;

FIG. 6 is an exploded perspective view thereof;

FIG. 7 is an exploded rear perspective view thereof;

FIG. 8 is a front perspective view of the bottom portion of the tag assembly of FIGS. 1-7 showing the bottom portion of the tag assembly in an alternate state during a process of separation;

FIG. 9 is an exploded front perspective view thereof;

FIG. 10 is an exploded rear perspective view thereof;

FIG. 11 is a rear perspective view of the top portion of the tag assembly of FIGS. 1-7 showing the top portion of the tag assembly in an alternative state during a process of separation;

FIG. 12 is an exploded perspective view thereof; and,

FIG. 13 is an exploded rear perspective view thereof.

The even length broken lines in the drawings are for the purpose of illustrating portions of the tag assembly that form no part of the claimed design. The uneven length broken lines in the drawings are used for the purpose of demonstrating the relationship between the elements in the exploded views and form no part of the claimed design.

1 Claim, 12 Drawing Sheets
